By C. S. Whitman

Attorney.

UNITED STATES PATENT OFFICE.

WILLIAM THOMAS SEYMOUR, OF STOCKTON-ON-TEES, COUNTY OF DURHAM,
ENGLAND.

LID OR COVER FOR METALLIC OR OTHER RECEPTACLES.

SPECIFICATION forming part of Letters Patent No. 397,391, dated February 5, 1889.

Application filed March 24, 1888. Serial No. 268,445. (No model.) Patented in England February 7, 1887, No. 1,876; in France August 12, 1887, No. 185,301; in Germany August 26, 1887, No. 43,733; in India January 10, 1888, No. 97; in Belgium February 7, 1888, No. 80,565, and in Canada February 7, 1888, No. 28,654.

To all whom it may concern:

Be it known that I, WILLIAM THOMAS SEYMOUR, a subject of the Queen of Great Britain, residing at Stockton-on-Tees, in the county of Durham, England, have invented certain new and useful Improvements in Metallic or other Vessels and in Covers Therefor, (for which I have received Letters Patent in England, No. 1,876, dated February 7, 1887; in France, No. 185,301, dated August 12, 1887; in Germany, No. 43,733, dated August 26, 1887; in India, No. 97, (No. of 1888 register,) dated January 10, 1888; in Belgium, No. 80,565, dated February 7, 1888, and in Canada, No. 28,654, dated February 7, 1888;) and I do hereby declare that the following is a full, clear, and exact description of the invention, which will enable others skilled in the art to which it appertains to make and use the same.

My invention relates to improvements in metallic or other receptacles—such as the tin cans or boxes ordinarily used for inclosing meat, fish, or other material, which boxes or cans require to be closed up securely, whether to exclude air or to endure the treatment to which they are usually subjected in packing and transmission from producer to consumer, and afterward require to be opened with facility. Boxes or cans employed for this purpose are often closed up by having the lid or cover soldered onto the rim of the box or can, which has to be ripped open to obtain access to the inside of the box or can. Attempts to overcome the objections to this mode of closing up this class of boxes or cans have resulted in constructing them with specially-formed rims, into which specially-constructed lids or covers can be made to fit, so that a detached lever of a simple character can be applied to the under side thereof and employed to force the lid or cover from the box or can. The essential features of my invention are a simple means of applying leverage to the cover or lid, combined with means for fitting the cover or lid into the end of the box or can, so that by attaching the lever to the upper or outside surface of the lid or cover the rim of the said box or can which extends beyond the top of the lid or cover can be employed as

the fulerum for applying the lever to force up 50 the cover or lid, to which it also affords protection from external pressure.

And in order that my invention may be fully understood, I will now proceed to describe it by referring to the accompanying 55 drawings, in which sectional views of boxes or cans constructed and furnished with levers in accordance with my invention are illustrated in Figures 1, 3, and 5, the corresponding views in plan being illustrated, respectively, in Figs. 2, 4, and 6.

In order to obtain a compact and close fit between the cover or lid *a* and the box or can *b*, I turn up the edge of the cover or lid *a* to form the rim *c*, which is inclosed within 65 the corresponding rim, *d*, of the box or can *b*, and in order to obtain the requisite degree of tightness in the fit between these rims and to facilitate the withdrawal of the lid when required I prefer to give to these rims a slight 70 and corresponding taper, the lid or cover practically forming a tapered plug inclosed by the rim *d*, the edge of which extends beyond the rim *c* and is rounded or wired over or otherwise rendered stiff, and serves both as 75 a guard to protect the lid or cover from external pressure and as a fulerum for the lever *e*, which is shown in the figures as permanently attached to the lid or cover *a* in a suitable manner. A ledge, *d'*, forms a plug-seat 80 within the box or can *b* in any suitable manner, such as that illustrated in Figs. 1 and 5, for fixing the position of the lid or cover *a* when pushed into the box or can its proper distance; but I prefer as an effective and 85 simple means of providing the requisite seat or ledge *d'* to unite the rim *d* to the box or can *b* in the manner clearly illustrated in Fig. 3, in which a difference is provided between the internal diameters of the box or can *b* 90 and the rim *d*, which forms the ledge or seat *d'* for the cover or lid *a*, the rim *d* being provided with a wire-shaped edge, *d*², to make it stiff to serve as the fulerum for lever *e*, and to protect the lid or cover fitted into it. The 95 advantage of this mode of fitting the cover to the can, in addition to that of simplicity of construction, is that such a ledge or seat, while

serving its purpose of supporting the cover *a*, presents no obstacle to the discharge of the contents of the box or can, whereas when the seat or ledge forms an internal flange or projection extending into the box or can an obstruction is formed, which is detrimental to effecting a complete clearance thereof by affording a lodgment for a residue of the contents.

10 In order to force up the lid or cover *a* to open the box or can *b*, which, it is obvious, cannot be done by any form of lever applied to the under side thereof, one or more levers, *e*, are attached to the lid or cover *a*. Figs. 1 and 2 illustrate a box or can provided with one lever only. In Figs. 3 and 4 three levers are provided. Each lever fits into a socket, *m*, secured to the lid or cover, to enable it to be turned over the rim or down on the lid, as required. In Figs. 5 and 6 I illustrate a form of lever designed to turn round the circle, so as to be applicable at any part of the circumference of the lid or cover *a*. This is effected by providing a lever, *e*, precisely similar to the levers illustrated and described with reference to Figs. 1, 2, 3, and 4; but instead of turning in a socket fixed in position near the edge of the cover or lid the lever is hinged to the bar *e'*, turning round on the pin *f* in the center of the lid or cover *a*. *a'* is a flange extending over the lid or cover, so as to overlap the free end of the bar *e'* to hold it down when resisting the strain produced by applying the lever *e*.

35 Having now described my invention and in what manner the same may be carried into effect, what I claim is—

1. As a new and improved article of manu-

facture, a can or box having its sides continued above its top, a seat formed in the top thereof, 40 and a cover resting therein provided with a lever pivoted thereto, whereby the said continued portion of the sides of the said can or box acts as a fulcrum for the said lever in the operation of the same.

2. As a new and improved article of manufacture, a can or box having its sides continued above its top and strengthened, a conically-shaped seat formed in the top thereof, and a cover resting therein provided with a lever 50 attached thereto and bearing upon the said strengthened portion of the sides, whereby the cover may be withdrawn from its seat.

3. The combination, in a cover, of a flange, *a'*, extending over the outer periphery thereof, a bar pivoted to the cover, the outer end of the said bar being held by the said flange, and a lever pivotally attached to said bar, as and for the purpose described.

4. The combination of a cover having a 60 flange, *a'*, extending over the outer periphery thereof, a bar pivoted thereto, the outer end of the said bar being held by the said flange, a can having its sides continued above its 65 top and strengthened, a seat formed in the top of the said can in which the said cover rests, and a lever pivotally attached to the said bar and adapted to raise the cover, as and for the purpose described.

In testimony whereof I affix my signature in 70 presence of two witnesses.

WILLIAM THOMAS SEYMOUR.
